UNITED STATES PATENT OFFICE.

ABRAHAM DEUTSCHMEISTER, OF NEW YORK, N. Y.

ENVELOP.

1,223,569.

Specification of Letters Patent. Patented Apr. 24, 1917.

Application filed June 21, 1916. Serial No. 104,860.

To all whom it may concern:

Be it known that I, ABRAHAM DEUTSCHMEISTER, a citizen of the United States, and a resident of New York city, in the county 5 of New York and State of New York, have invented certain new and useful Improvements in Envelops, of which the following is a specification.

This invention relates to mailing envelopes, 10 particularly of the type adapted for use in mailing matter at third class mail matter rates.

One object of the invention is to provide an envelop of this character in which the 15 contents is securely held.

Another object is to provide an envelop of this character which has the appearance of a sealed envelop and yet can be readily opened for inspecting the contents as required for third class mail matter.

A further object is to provide an envelop which may be made up at small cost and is readily manipulated.

The various further objects and advantages will more fully appear from the detailed description and the features of novelty will be particularly pointed out in the 25 claims.

In the drawings illustrating the invention,

Figure 1 is a development of the blank from which the envelop is formed.

Fig. 2 is a perspective view of the envelop showing the manner in which it is 35 folded and assembled.

Fig. 3 is a rear view of the envelop as assembled.

Fig. 4 is a face view in perspective illustrating the manner in which the slot is 40 opened to insert or remove the contents.

Fig. 5 is a face view of the envelop as sealed for mailing.

Fig. 6 is a similar view of a modified form with a straight instead of curved slot.

Fig. 7 is a development of a blank illustrating a further modified form.

Fig. 8 is a rear view of the assembled envelop made up from the blank illustrated in Fig. 7.

50 Referring in detail to the drawing, particularly to Figs. 1 to 5, the envelop is formed with the face portion 10 and back portion 11 and the gummed flaps 12, 13 and 14 formed preferably on the face portion to unite the same with the back portion.

Formed in the face portion 10, adjacent to

one end thereof, is a slot 15 of preferably curved contour, and from the adjacent end of the back portion 11 extends a flap 16 which is tucked into the interior of the envelop when the flap 12 is pasted over the back portion, as clearly appears from Figs. 2 and 4.

When the envelop is made up, the flap 16 is concealed in the interior of the envelop 65 and serves the function of retaining the contents when inserted in the envelop. Thus, when it is desired to insert the matter in the envelop, pressure is applied to the longitudinal edges 17, 18, (Fig. 4), opening the slot 70 15. The matter may be then readily inserted through the slot and the concealed flap 16 folded thereover in the interior of the envelop. If desired, moreover, the concealed flap 16 may be passed through the 75 slot, forming a lock for securely holding the contents.

I prefer to use a curved slot for the reason that the envelop may be more readily opened. However, if desired, a straight slot 80 15^a may be used as shown in Fig. 6.

In the modified form illustrated in Figs. 7 and 8, the slot 15^b is disposed in the back portion 11 and the flap 16 is folded back on itself at the interior of the envelop adapted 85 to pass through the slot 15^b as in the other form described. The gummed flap 12^b is preferably provided with the extensions 12^c at the extremities thereof forming reinforcements for the end of the slot 15^b, thus 90 preventing the tearing of the paper. In this construction, the face portion 10 is left entirely free and smooth for the addressing.

It will thus be seen that I have provided an envelop which may be used for sending 95 mail at third class mail rates and, at the same time, the contents is securely held in the envelop and may be readily inserted and removed. The envelop is inexpensive to make and efficient in use.

Having thus described my invention, I 100 claim as new and desire to secure by Letters Patent:

1. An envelop comprising a face portion and a back portion, a slot formed in one of 105 said portions, and a normally concealed flap freely disposed at the interior of the envelop opposite said slot, whereby the matter may be inserted into the envelop and retained by the concealed flap.

2. An envelop comprising a face portion and a back portion, a slot formed in one of 110

- said portions, and a normally concealed flap freely disposed at the interior of the envelop opposite said slot, said flap being of a proportion so as to pass from the interior of the envelop through the slot to the exterior so as to lock the contents within the envelop in place.
3. An envelop comprising a face portion, a back portion, a flap freely extending in the interior of the envelop from one of the lateral edges of one of said portions, there being a slot formed in one of said portions in juxtaposition with said flap, gummed flaps on the edges of said portions sealing the edges of the envelop about the entire perimeter of the same, said first mentioned flap being of a size to pass from the interior of the envelop through the slot so as to lock the contents of the envelop within the same.
- 20 4. An envelop comprising a face portion, a back portion, gummed flaps extending from the edges of the face portion, a flap extending freely from one of the edges of the back portion within the envelop and normally concealed therein, said back portion being formed with a slot adjacent said flap
- 25 through which slot the flap may pass to the exterior of the envelop to lock the contents of the envelop within the same.
5. An envelop comprising a face portion, a back portion, gummed flaps extending from the edges of the face portion to seal the envelop about its perimeter, a flap extending from one of the edges of the back portion within the envelop and normally concealed therein, said back portion being formed with a slot adjacent said flap through which the flap can pass to the exterior of the envelop to lock the contents of the envelop within the same, the gummed flap which is attached to the edge of the back portion adjacent the slot being formed with portions passing across the ends of the slot to reinforce the material thereabout.
- 30 35 40 45

Signed at New York city, in the county of New York, and State of New York, this 15th day of June A. D. 1916.

ABRAHAM DEUTSCHMEISTER.
